UNITED STATES PATENT OFFICE.

GARRETT J. COUCHOIS, OF NEW YORK, N. Y.

DESIGN FOR A WHISTLE.

SPECIFICATION forming part of Design No. 31,876, dated November 21, 1899.

Application filed October 21, 1899. Serial No. 734,410. Term of patent 14 years.

To all whom it may concern:

Be it known that I, GARRETT J. COUCHOIS, residing at New York, in the county of New York and State of New York, have invented 5 a new and useful Design for a Whistle, of which the following is a specification, reference being made to the accompanying drawings, forming part thereof—

Figure 1 is a side elevation. Fig. 2 is a 10 front elevation, and Fig. 3 is a plan view looking from above.

The invention relates to a new and original 15 design for a whistle; and it consists, essentially, in the general outer conformation of such portions of the same, as will hereinafter be specifically described.

The characteristic feature of my design consists of a nose-piece 3, which in cross-section or in outline when viewed from above, as in

Fig. 3, is approximately V-shaped, while each 20 side thereof tapers more or less and terminates in a rounded extremity when viewed as in Figs. 1 and 2.

1 indicates the whistle-body, and 2 the air-tube, such as are used with the nose-piece, 25 the point of connection between the latter and the tube being indicated at 4.

Having thus described my new and original design, what I claim is—

The design for a whistle as herein shown 30 and described.

In testimony whereof I affix my signature in the presence of two witnesses.

GARRETT J. COUCHOIS.
